PILE AND METHOD OF SINKING SAME.

1,248,296.

Specification of Letters Patent. Patented Nov. 27, 1917.

Application filed February 10, 1915. Serial No. 7,273.

To all whom it may concern:

Be it known that I, ELMER F. ESTES, a citizen of the United States, and a resident of Lincoln, in the county of Lancaster and State of Nebraska, have made certain new and useful Improvements in Piles and Methods of Sinking Same, of which the following is a specification.

My invention relates to improvements in piles and piling systems and also to a method of sinking the same and like objects and has for an object to utilize the hydraulic jet system in connection with piles and sinking them by an up and down motion of the same; another object is to provide a simple convenient and efficient method of sinking such piles and the like.

My invention is particularly adapted to assist in sinking concrete or other cement piles or piling and in carrying my invention into effect I embody the well-known principle that a jet of water easily displaces earth in its various forms; and I provide a specially formed pile and means for excavating under and around the pile and to maintain a supply of water all around the pile at the same time and to prevent the earth from settling about the pile and holding it as against descent which is intermittently and periodically given to the pile as one of the steps of my method.

In the known systems of jet piling, pile jetting, or jetting piles, wherein a jet of water is delivered below a pile, post or similar object to loosen the earth, the purpose is only partially accomplished; the pile as it is driven has a tremendous side resistance and renders the process of sinking piles very slow and unsatisfactory. To obviate this I propose to use a central jet at the lower end of a pile in combination with the specially formed lower end thereof to excavate, the force of the jet mixing earth and water into a very thin mud and throwing such mixture in an oblique direction outwardly and upwardly and channeling on all sides of the pile, the pile during such treatment being given a reciprocal up and down or jig motion, the throwing of the mixture being accomplished by the sudden dropping of the pile to nearly the bottom of the excavation made by the jet, producing by such throwing, channels of water upward along all sides of pile.

To accomplish these and other objects my invention consists in the peculiar construc-

tion, arrangement and combination of parts of a pile; and the method of sinking the same, reference being had to the accompanying drawings in which,

Figure 1 is a top plan view of a pile and rig to assist in sinking the same,

Fig. 2 is a side elevation of concrete pile embodying my improvements,

Fig. 3 is an enlarged sectional view of the lower end of the same on line 3-3 of Fig. 2,

Fig. 4 is a horizontal section on line 4-4 of Fig. 2,

Fig. 5 is a perspective view of a portion of the rig for securing the jet pipe to the pile and a portion of the jet pipe,

Fig. 6 is a cross sectional view of a modification,

Fig. 7 is a fragmentary perspective view of a modified form of nose for a pile,

Fig. 8 is a similar view of another form.

To carry out my improvement, I may use a solid concrete or a wooden pile 10 which may be of any suitable shape in cross section and provide it with an inverted or frusto-pyramid shaped head or nose 11; the slant of the face of which will usually be about 45°; in each face of the slanting taper a groove 12 is made which begins in the middle of each lower inclined face of the taper and extends up the vertical sides of the pile a suitable distance depending on the size of the pile; the formation of these grooves creates channels that slant outwardly and upwardly at a sharp angle, say 15° from the perpendicular; at the lower ends of the vertical sides of the pile and on each side of the grooves 12 are the projecting knobs 13 which are for the purpose of abrading the earth bore around the pile and make room for the corners as the up and down motion of the pile takes place.

To insure delivery of the jet of water at the lower end of the pile and centrally, I have devised a rig for application to the pile which consists of a rod 14 on one side of the pile which passes through a yoke 15 resting on a fulcrum 16 placed on the top of the pile; at the opposite end of the yoke the jet pipe 17 is secured being connected to a hose 18 which is connected up to a suitable pressure water supply; the jet pipe 17 extends downwardly along one side of the pile and has a 45° L 19 so that it may lie in one of the grooves 12 and extends below the lower end of the pile and is then provided with another 45° L as at 20. To hold the

lower end of the pipe 17 in place, the rod 14 extends downwardly along the side of the pile diametrically opposite the jet pipe and is then bent inwardly at 21 to lie in 5 the groove on the side and extending down below the end of the pile is bent horizontally and formed into a ring or eye 22 in which is seated the straight lower and enlarged end 20 of the jet pipe; by tightening 10 the nut 22 on the threaded upper end of the rod 14 the yoke 15 acts as a lever with 16 as a fulcrum and draws the parts of the rig into close contact with the pile and holds the same there while in use.

15 In Fig. 6 I have shown a modified form of pile in which the grooves 12^a are disposed at the angular corners of the pile 10^a and with this form the water pipe 17 may be placed at the corner.

20 In using my improvements, the pile is to be sunk with one central jet in conjunction with an up and down or jig motion of the pile, through the agency of a supporting derrick or crane, the purpose being to 25 excavate under the pile and to maintain a supply of water and new mixture all around the pile at the same time and to prevent the earth from settling about the pile and holding it against descent. The parts being as

30 in the position shown in Fig. 2 a stream of water is forced through the pipe 17 and issues as a jet at 20 the force of the jet mixing the earth and water into a very thin mud and this mixture is thrown in a slanting 35 direction outwardly and upwardly through the grooves 12 and 12^a on all sides of the pile; this is done by holding the pile vertical by suitable mechanism and first projecting the jet downward centrally to 40 excavate an opening in the earth; then lowering pile, continuing the jet until the nozzle 20 nearly touches the bottom; then elevating the pile a few feet as indicated in dotted lines in Fig. 2 and again lowering 45 suddenly, and continuing this operation until sufficient depth has been attained; during this operation the slanting grooves 12 cause the water and mixture to be thrown sidewise outwardly and upwardly washing 50 the sides of the bore or opening in the earth thus producing a number of channels all around the pile and creating upward currents, so that the pile can be quickly and positively sunk to its required position.

55 By forming the grooves on all sides of the pile the corners and edges act as chisels cutting the water when dropped into a hole and throwing the water mixed with mud each way and crowding the mixture into 60 the grooves where, by virtue of their shape and direction, it is thrown outwardly and upwardly because of the weight and rapidity of the descending pile; the downward jet is at the same time churning the 65 water and detached earth into thin mud,

and at each successive descent of the pile; and the mixture cannot return during the withdrawal of the pile on its retraction, of a few feet preparatory to the next descent, because the stream is keeping the bottom 70 of the hole filled with new mud and mixture.

I may mold the pile into one solid piece of concrete, cement or the like with its peculiarly shaped nose and slanting grooves 75 or I may provide the lower end with a metal point 23 having slanting grooves 12 and secured to the lower end of the pile by bolts 25 as shown in Fig. 3; or, I may inclose the end with an inverted frusto-pyramidal or frusto-cone shaped jacket provided with the necessary grooves and suitably secured to the pile body portion; to sink wood piles such a metal jacket might be used, and a weight placed on the top would be sufficient to sink them without resorting to a hammer or pile driver.

The pile may also be made round or other shape so long as the end is tapered and shaped in accordance with my invention and 90 provided with slanting grooves to throw the water and mud mixture outwardly and upwardly against the bore on all sides of the pile.

To remove the rig and jet pipe the upper 95 end of rod 14 is released from the yoke 15 so that the eye 22 at the lower end may be dropped below the end of the jet pipe whereupon all the parts become separated and may be withdrawn from the space surrounding the piles. Other means of securing the jet pipe may be used as found desirable and expedient.

In Fig. 7 I have shown the nose end of 105 the pile with an enlargement of greater diameter than the body of the pile, which aids in opening up the bore; this form is also provided with the slanting grooves 12^b.

In Fig. 8 is shown a round pile the lower or nose end 11^a of which is frustocone 110 shaped and provided with slanting grooves or channels 12^c.

My invention is designed to utilize nature's channeling tendency, by furnishing a plurality of exits or openings for exits and 115 forcing a mixture of earth and water through those exits, instead of permitting all the mixture to pass up in one channel.

I claim.

1. The herein described method of sinking piles by an intermittent up and down movement thereof consisting in forcing an exterior stream of water centrally downward from the lower end of the pile forming a mud mixture and then causing the deflection of said mixture outwardly and upwardly around the pile on all sides thereof.

2. The herein described method of sinking piles consisting in inserting a pile in a bore, imparting an intermittent up and 130

down motion to the same, continuously projecting a jet of water centrally downward from the lower end of the pile during said up and down motion forming a mud mixture and causing the deflection outwardly and upwardly of said mixture on all sides of the pile.

3. The combination with a pile to be sunk in the earth said pile having obliquely disposed grooves at its lower end, of a water jet pipe held in one of said grooves and projecting downward centrally from the pile, a nozzle at the lower end of the pipe, a rod disposed along the opposite side of the pile and means carried by the rod for engaging the pipe and supporting the pipe at its lower end, and means for clamping the water pipe and rod to the pile.

4. The combination with a pile to be sunk in the earth, said pile having a tapering lower end, grooves in each slanting face of the same, said grooves extending above the base line of the taper and into the body of the pile, the direction of the grooves being obliquely upward, a water discharge pipe disposed alongside of the pile, a nozzle at the lower end of the pipe projecting axially downward below the pile, of means extending down the diametrically opposite side of the pile and bent to lie within a groove, means at the lower end of the aforesaid means to receive and center the nozzle of the water pipe and a yoke at the top of the pile to clamp the pipe and first mentioned means to the pile.

5. A pile comprising a body portion, a tapered lower end and knobs projecting from each face of the body at the corners thereof adjacent the tapered lower end.

40 6. The combination with a pile to be sunk in the earth, the nose or lower end of the

pile having the form of a cone frustum or an inverted pyramid, channels lying partly in the slanting faces of the nose and partly in the body of the pile, of a water discharge pipe disposed along one side of the pile and lying in one of the grooves, a jet nozzle projecting downwardly from said pipe at the apex of the pyramid or cone frustum, a rod or bar disposed diametrically opposite the water pipe and having an eye or opening at its lower end to receive and center the jet nozzle, a yoke at the upper end of the pile and embracing the upper ends of the rod and pipe and clamping the same to the pile and a water supply member coupled to the upper end of the pipe.

7. A pile of the character described comprising a body portion and diametrically opposite vertically disposed grooves at the lower end thereof, knobs having sharpened corners and projecting from each face of the lower end at the corners thereof.

8. The combination with a pile comprising a body portion and diametrically opposite vertically disposed grooves at the lower end thereof and knobs having sharpened corners projecting from each face of the lower end at the corners thereof, of a rigging consisting of a water jet pipe held in one of said grooves and projecting downward centrally from the pile, a nozzle at the lower end of the pipe, a rod disposed along the opposite side of the pile, and means carried by the rod for engaging the pipe and supporting the same at its lower end, and means for clamping the water pipe and rod to the pile.
